COAGULATING APPARATUS

Walter H. Green, Geneva Township, Kane County, Ill., assignor to Infilco Incorporated, Chicago, Ill., a corporation of Delaware

Original application September 3, 1947, Serial No. 771,968. Divided and this application August 29, 1949, Serial No. 112,856

6 Claims. (Cl. 259—6)

1

This invention relates to a method and apparatus for the mechanical flocculation of solids in liquids, with or without the use of a chemical flocculant.

A main object of my invention is to provide a form of coagulating apparatus whereby or wherein there is set up a pattern of flow of a form particularly favorable to coagulation.

A specific object of my invention is to set up in a flocculation, or coagulation, zone or apparatus a plurality of individual coagulating units, each of which, though not separated from the others by partitions or baffles, maintains a separate zone with a three dimensional flow pattern affording exceptional opportunity for gentle contact of flocs, or coagulum, and for gentle passage from one zone to another.

Another object is to flocculate solids in a liquid by a vortex type of agitation, whereby, due to the intricate pattern of flow in all three dimensions without undue turbulence, the solids in the liquid readily aggregate into larger and denser particles than has been customary heretofore.

Another object is to provide a flocculation, or coagulation, assembly which will function equally well with a horizontal or a vertical through flow and regardless of the location of the inlet and outlet.

Another object is to provide an apparatus that will set up and maintain in the liquid within a basin or chamber that forms part of the apparatus, a type or pattern of flow that in addition to inducing very numerous particle contacts or collisions favorable to floc growth also includes in one or more closed circuit flows all the liquid in the basin or chamber whereby all the volume of the basin is utilized, short circuiting is prevented and a substantially uniform velocity is imparted to the liquid in all parts of the basin.

Another object is to provide, as one member of apparatus of the type referred to, a rotor, the rotor being so fashioned and proportioned and so placed that during operation it will constantly draw in toward itself a major flow of liquid along or in the direction of the shaft on which it is maintained and will discharge this liquid radially outward from the shaft and in substantially equal amount in all directions.

Other objects of the invention will become apparent upon consideration of the specification and claims which follow.

In the clarification of turbid liquids, as by sedimentation or filtration, it is often found that

2

fine solids in suspension in the liquid to be clarified are exceedingly difficult to remove, being too light to settle in any reasonable time and too small to be retained by any practical filter medium. Liquids containing such fine solids are usually pretreated by coagulation, or flocculation, (the terms usually being used interchangeably) to improve the settling or filtering qualities of these solids. In the coagulation step the liquid, which customarily will be dosed, either before or during the treatment, with floc-forming chemicals, is subjected to gentle agitation for a period of time to afford repeated contacts between solid particles, or flocs, in the liquid. Such contacts promote their aggregating, as by agglomeration and coagmentation, to form larger particles which are conditioned to settle or filter more easily.

One of the oldest and simplest forms of providing gentle agitation is the baffled basin. Baffles of various kinds, such as for example the so called "round-the-end" type, the "under-and-over" type, have been widely used for this purpose. However the agitation provided by the changes in direction caused by such baffles is often insufficient for proper coagulation of large flows of liquid.

More recently mechanical flocculators have come increasingly into use for coagulating liquids. These flocculators have paddle agitators of the revolving, or sometimes the reciprocating type. The paddles, usually fixed to horizontal shafts, are slowly moved through the liquid to impart thereto a gentle stirring motion. The degree of agitation that may be imparted to the liquid in this manner is quite limited, as the flocs produced by this kind of agitation are fragile and delicate and subject to breaking up by turbulence.

It was generally found that this type of agitation, in an unbaffled basin, did not prevent liquid from flowing in a continuous horizontal flow along the surface of the liquid, or along the bottom of the basin, or both, from inlet to outlet, for, due to the character of the particles, not sufficient positive energy could be applied to the liquid with the stirring devices used to break up this tendency. To avoid such objectionable short-circuiting of part of the liquid, paddle agitation usually has been combined with various types of baffle arrangements. By interposing round-the-end or over-under baffles or the like, the liquid was forced to take a circuitous path which prevented its short-circuiting from inlet to outlet. Between pairs of baffles individual

agitation cells, or units, were thus set up, where-in the paddles caused a gentle agitation of the liquid. Thus the general forward flow of liquid through the basin was subject to deflection, laterally or vertically, by the baffles, and to some kind of agitation in the individual cells by rotation of the paddles. The combined motions resulted in particle collisions conducive to coagulation. In all such apparatus the most apparent and greatest amount of movement of the liquid in passing through the coagulating space is the continuous longitudinal forward movement from inlet to outlet, the moving paddles merely causing some local turbulence in this pattern of flow. Since the greatest permissible velocity of such paddles is generally considered to be $1\frac{1}{2}$ to 2 feet per second it is obvious that a very elaborate paddle system is required to secure enough collisions to produce maximum coagulation. I have found that a greater number of particle collisions suitable for producing coagulation can be had in an apparatus and by the flow pattern herein described in the same or less space and time. It will be noted also that with the apparatus and flow pattern herein proposed the particle collisions are not due primarily or chiefly to local and temporary eddies but to sustained, more or less parallel, somewhat distorted flows or currents between which there is a shearing or rolling action tending to roll up larger flocs.

It will be obvious that a combination of mechanical agitation and baffles, such as used in the prior art, is a very expensive way of providing coagulation. Moreover the flocs formed by this treatment are quite fragile and light so that great care is needed in handling them to avoid breaking them up. Another drawback of such prior art structures is that they have generally submerged bearings and that the agitators are not accessible for inspection and repair without draining the entire basin.

It is the principal object of my invention to avoid these drawbacks and to obtain good flocculation, with the formation of tougher and heavier flocs, in a cheaper manner. More specifically I have found that I can eliminate all baffles and still maintain what may be called self-contained agitation zones which effectively prevent short-circuiting of liquid from inlet to outlet. At the same time I may provide a structure free of submerged bearings, and which affords easy access to individual agitators during operation of the apparatus.

These improvements are obtained by using, instead of the paddle agitators of the prior art, a type of rotor which pumps a large volume of liquid and establishes in the liquid what may be termed a closed cycle vortex, and by mounting and dimensioning such rotor, or rotors, in such a manner that the vortex or vortices set up embrace the entire liquid in the basin. I am aware that rotors of the general type employed herein are not new but have been used heretofore for mixing of liquid and chemicals, for stirring liquids to aid in solution of solids or to keep solids in suspension, or the like, but as far as I know, they have not been used in, and not been considered suitable for, flocculation. The vortex created by these rotors has not been thought a proper type of agitation for coagulation, as the general theory of the prior art of flocculation was that only very gentle agitation, without turbulence was permissible. I believe that I am the first to discover the advantages of such rotors for the present purpose and the need for their being properly designed and placed relative to other

parts if all possible benefits are to be had, and to disclose the principles and limitations of such design and placing.

I have found that the vortex type agitation is very suitable for coagulation and affords many advantages over paddle agitation. The number of collisions between particles of different size and age which lead to coagulation and amassment of flocs, is by far higher in this type of agitation. This is due to the intricate flow pattern set up by these rotors, wherein the liquid moves in all three dimensions instead of the simple rotation of the prior art of coagulation. Therefore flocs form more rapidly and become tougher and heavier. Furthermore the vortex set up around a rotor of this type tends to maintain itself, i. e. the liquid approaching a rotor on its way through the basin is positively pulled into, and held for a period of time in, the vortex. It is desirable that the amount of the vortex flow is such that all liquid in its zone of influence normally passes at least twice through the vortex. Thus the liquid is deflected from its general forward flow through the basin from inlet to outlet, the vortex set up by such a rotor accomplishing what prior art had to accomplish by baffles; it prevents short-circuiting. With a rotor of this type, the direction of forward flow through the flocculation chamber is of no importance.

Whether the general direction of through flow be horizontal, as is usual in separate coagulating apparatus, or vertical, as frequently used in a flocculation chamber which is surrounded by a sedimentation chamber, the liquid will be deflected from the forward flow and held for a period of time in the vortex. Therefore, the liquid may enter the flocculation chamber at any convenient point and be withdrawn from any convenient point, as long as the rotor is interposed in the path of the liquid from inlet to outlet. The same is not true of paddle agitation, where a definite relation must be established between the direction of the through flow and that of the rotation set up by the paddles and the inlet and outlet therefore carefully located.

In order to obtain these results the rotor has to be carefully dimensioned and proportioned and properly positioned in relation to the liquid in the basin. Thus, I have found, for instance, that the relative length of the blades to the diameter of the rotor, is of great importance with regard to the flow pattern caused by rotation of the rotor. Too long blades cause the liquid which is drawn into the vortex to flow along the shaft of the rotor in a very tight spiral that may cause breaking up of flocs. Too short blades, on the other hand, do not pump a sufficient volume of liquid into the vortex to utilize all the liquid in the basin. I have found that the underwater length of the blades may range, depending on other circumstances, from about one-fourth to about one-third of the diameter of the rotor. Similarly the diameter of the rotor must be properly proportioned to the size of the basin. With a rotor mounted on a vertical shaft a diameter ranging from about one-fourth to about one-fifth the width or diameter of the basin has been found satisfactory. It will be understood that such dimensions are not sharply critical and may vary considerably with such things as the number of blades provided, the shape and dimensions of the basin, the number of rotors used and the nature of the liquid to be treated. The important thing is that the flow set up is of the closed cycle vortex type and embraces substan-

tially all liquid within the sphere of influence of a rotor, the liquid being drawn into the rotor and then thrown outwardly substantially uniformly in all directions.

Obviously, to obtain the same amount of agitation the size of the rotor can be smaller with higher peripheral speeds and must be larger with lower speeds. I have found rotors of the dimensions mentioned and with a peripheral speed of 2 to 3 feet per second very satisfactory.

The rotor may be mounted in various ways in the basin. In a preferred form of my invention the rotor is mounted on a vertically extending shaft which may be supported on a beam or arm across the basin, or on a supporting column, in which case I may provide a walkway extending from the side of the basin to the column to provide access to the agitating unit. In one preferred form of the invention the rotor is mounted on a hinged support so that it can be swung over to the side wall of the basin.

With a rotor mounted on a vertical shaft and the blades extending vertically from the underside of a horizontal plate I have found it advantageous to mount the rotor so that the plate is above the liquid level. I have found that when the plate is immersed in the liquid, its rotation will sometimes cause a rotational flow of the surface layers of the liquid around the basin, which is conducive to short circuiting, and that at any rate, the vortex in such case will not extend into the upper layers of the liquid so that no full benefits are had.

My invention will be more fully understood by reference to the detailed description which follows and to the drawings which show preferred embodiments of the invention, and in which like reference characters designate similar elements.

Figure 1 is a plan view of a preferred form of a coagulation apparatus according to the invention, showing two forms of rotor support;

Figure 2 is a longitudinal vertical cross-sectional view of the apparatus of Figure 1;

Figure 3 is a vertical transverse view of a modified apparatus suitable for vertical through-flow and showing a swingable or hinged support of the rotor; and

Figure 4 is a partial vertical cross-sectional view of a coagulation basin with the rotor supported on a column.

The apparatus of my invention shown in Figures 1 to 4 comprises a basin 10 of conventional size and shape but without conventional baffles. The basin may be of any desired shape, such as rectangular, as shown in Figure 1, or round, as the embodiment of Figure 3. The basin 10 has a substantially flat bottom 11 and upstanding boundary walls, such as side walls 12 and 13, and end walls 14 and 15, or in the case of a round basin, a boundary wall 16. Ordinarily a walkway 18, such as is shown in Figure 4, will run along the top of the basin 10. Liquid to be treated may enter the basin in any suitable manner. In Figures 1 and 2 it is shown as entering at one end of the basin as through an inlet 20, discharging into a distribution launder 21. Treated liquid is withdrawn from the basin at a location functionally remote from the inlet, as through an outlet pipe 24 leading from the other end of the basin. While the liquid is shown in Figures 1 and 2 as entering at one end of the basin through distribution launder 21 and as being withdrawn from the opposite end of the basin, such location of the inlet and outlet and

the use of a distribution launder do not form an essential part of my apparatus.

The direction of the through-flow is of no importance as my apparatus lends itself equally well for vertical as for horizontal through-flow. Thus, in Figure 3 the liquid is shown as entering near the bottom through inlet 20a and is withdrawn near the top through outlet 24a, but the location of the inlet and outlet could be reversed and the inlet be near the top and the outlet near the bottom. One outlet 24a is shown in Figure 3 (and in a separate coagulation chamber the inlet 20a and the outlet 24a may be simple pipes extending through the same wall of the basin), but a plurality of ports 24a would be used, or the liquid be permitted to overflow the wall of the coagulating chamber where the flocculated liquid is discharged directly into a surrounding or adjacent settling chamber. Such relative location of inlet and outlet is permissible and no special means for distribution are needed because the rotor, when properly positioned, will immediately draw the incoming liquid into, and incorporate and retain it in, the vortex flow wherein it is mixed with and distributed through at least an equal quantity of liquid undergoing coagulation. The important thing with regard to the relative location of the inlet and outlet is that they are functionally—but not necessarily spatially—remote from each other. By functionally remote I mean that they are located so that the vortex or vortices set up in the basin are interposed in the path of the liquid from the inlet to the outlet. A drain 25 is provided in the bottom of the tank, so that the basin can be emptied if desired. The inlet 20, outlet pipe 24 and drain 25 will be provided with suitable valves, not shown.

One or a plurality of rotors 30 are provided in the basin 10. While two rotors are shown in Figures 1 and 2 it will be obvious that any number of rotors may be provided and that the number will be dependent on the size of the basin and of the individual rotor. In small basins a single rotor is satisfactory. Preferably, where several rotors are used and proportioned as above described, they are spaced apart a distance about equal to the width of the basin. This arrangement will establish what might be called "tangential vortices"—i. e. vortices in which the flow established by each rotor extends over to, and is tangent to, the vortex established by the adjacent rotor.

Each rotor 30 comprises a plurality of vertical blades 31 which may be mounted on any suitable supporting means, such as a spider, but which are preferably mounted on the underside of a plate 32, as shown. The diameter of the plate 32, or other support, may be from about one-fourth to about one-fifth the width or diameter of the basin. The blades 31 may be mounted on plate 32 either radially or at an angle to the radius. Preferably, at least twelve blades are provided. However, the peripheral distance between blades preferably should not be more than from 15 to 20 inches, so that with large rotors a much larger number of blades is desirable. The width of the blades 31 may be approximately one-seventh the diameter of plate 32 and their length from about one-fourth to about one-third the diameter of the rotor. The plate 32 is mounted on a shaft 33 which is driven by any suitable means, as by a motor 35 and a speed reducer 36. The plate 32 is mounted on the shaft 33, preferably at an elevation above the normal liquid level in the basin 10, as indicated by the dotted line L in Figure 2, but the

blades customarily will be substantially immersed in the liquid. This construction is preferred as obviously the plate 32 would interfere with, or distort, the vortex formed by the moving blades, and I have found that best results are secured when the natural shape of the vortex is not changed and the velocity imparted is relatively uniform throughout. Also the plate, if immersed, would consume additional power without corresponding benefit. As mentioned above, I have also found that when the plate is submerged, the liquid above the plate is not incorporated in the vortex but has a tendency to flow around the basin along its walls, which may lead to short circuiting. Such a flow is not desirable and it is therefore preferred, where a plate is used for supporting vertical blades, to mount it at an elevation above the normal liquid level.

The rotor and its driving assembly 35, 36 may be supported in various manners. As shown in Figure 1, at the left, the rotor is supported by a beam or bridge 40 which spans the basin, as shown. The motor 35 and speed reducer 36, from which the shaft 33 is suspended are mounted on the beam 40. In the customary narrow basin the rotor would be placed at the longitudinal axis of the basin. Obviously, in a wide basin, a plurality of rotors may be supported from each beam 40. The beam 40 will preferably provide a walk-way from the wall of the basin to the rotor or rotors.

Another kind of support is shown at the right hand end of Figure 1, and more clearly in Figure 3. In this embodiment of my invention a swingable, or hinged, arm or support is provided for each rotor-motor assembly, so that the entire assembly can be moved over to the wall of the basin for inspection or repair without interrupting the operation of the apparatus. Such support may comprise an arm 41 which is pivotally mounted on a wall of the basin by any suitable hinge 42, and extends over the basin, preferably above the normal liquid level therein. A brace 43 may be provided to give support to the arm 41 and will also be pivotally mounted on the basin wall, as by hinge 44. The arm 41 may be held against undesired horizontal movement by a bracket 45, as shown.

Another means of supporting the rotor 30 and motor 35 is shown in Figure 4. Here the motor and rotor derive support from an upstanding pier or column 50 rising from the floor of the tank. The shaft 33 is centrally and rotatably mounted on the pier and the plate 32 is affixed to the shaft 33 at an elevation above the normal liquid level in the basin. The blades 31 encircle the column and rotate thereabout. Preferably the column 50 will extend up to an elevation above the normal liquid level to avoid all submerged bearings. In this embodiment I may also provide a bridge 51, preferably of the cantilever type, as shown in Figure 4, extending from the wall of the basin to the rotor 30. In a larger basin, where several rotors are employed I may provide an individual stationary bridge for each rotor, or, as shown in Figure 4, a single movable bridge, which may serve a row of rotors.

Such a movable bridge may comprise a beam or arm 52 extending over the basin to adjacent the rotor and also extending a short distance outside the basin above the walkway 18. The outer end of the arm 52 may be held in place by means of a Z bar 53 which may be bolted to the walkway 18, as by bolts 54. On top of the side 75

wall 12 or 13 a rail 55 may be provided and a wheel 56 be mounted on the underside of the arm 52 and positioned to run along the rail 55. The arm 52 may be supported by a brace 57, as shown, which may carry a wheel 58 at its lower end adapted to run along the inside of the wall 12 or 13. The bridge 51 can be moved manually or by any suitable means, not shown.

It will be obvious that the motor need not be mounted as shown, supported above the basin, but can be placed to one side of the basin and supported in any suitable manner, as from a wall of the basin. In such case suitable gearing will connect the motor and the shaft of the rotor and such gearing may be supported from the beam 40, or the arm 41 or the column 50, as the case may be. Also the rotor instead of being at the top of the liquid in the basin can be at a lower level; for instance the shaft 33 could be extended to the floor of the basin and the rotor mounted near the lower end in inverted position with the blades extending upwardly from the plate 32. This would invert the vortex in the basin which might be of advantage in some cases, as for instance when dealing with relatively heavy precipitate.

The operation of my coagulator will be readily understood. The liquid to be treated in the coagulator customarily is dosed with a coagulant either before its entry into the basin 10, or during its treatment therein, or, in some instances, it may be subjected to mechanical flocculation alone. For both purposes my coagulator lends itself very well. Liquid to be treated may enter the basin, as shown in Figures 1 and 2, through inlet 20 and distribution launder 21, and is displaced forwardly to the outlet end of the basin, and thence into outlet conduit 24, leading to a settler, or filter, or the like, not shown. Or, as shown in Figure 3, it may flow through the basin in a vertical forward flow, as by entering at inlet conduit 20a near the floor and being withdrawn through outlet conduit 24a at a higher elevation. The inlet 20a and the outlet 24a may even be in the same wall of the basin, as shown in the figure. From this forward displacement from inlet to outlet the liquid is repeatedly deflected and drawn into, and held for a period of time in, the vortex set up by the rotor or successive rotors.

Such a vortex is distinguished from the rotational movement caused by the usual paddle agitation by its three dimensional flow pattern. While in the rotation of paddles through liquid the movement of the liquid is always in the same plane, in vortex coagulation the liquid moves through numerous planes. The vortex pattern has a flow which spirals outwardly in all directions at the top to the walls of the basin or the edge of its zone of influence; then spirals downwardly to the floor; then spirals inwardly from all directions along the floor to the axis of the vortex, which is substantially the axis of the shaft 33, and then spirals upwardly along the axis to the rotor, which imparts the outwardly spiraling flow at the top. The axis of the vortex may sometimes be at right angles to a general horizontal direction of flow through the basin or sometimes, as in vertical direction of flow, may be parallel to the flow. The relation of the vortex to the direction of flow is relatively unimportant. It is important, how-

ever, that the vortex flow caused by the rotor 30 is greater than the normal displacement through the basin 10, so that the vortex will overcome the normal forward displacement. Thus any portion of liquid approaching any vortex is prevented from passing across the vortex to the outlet, as it encounters a stronger stream of liquid spiraling counter-currently to the direction of displacement and then back to the rotor. Into this pattern the liquid approaching the vortex is forcibly incorporated and will remain part of the vortex flow for a period of time. Forward displacement from the vortex can only take place at the outside of the vortex flow (spiraling away from the rotor) so that it is impossible for a particle to flow across the basin without becoming incorporated in each succeeding vortex. It should be understood that each vortex is greater in volume and velocity than the forward displacement, and that it either is large enough to extend entirely across the basin laterally, or there will be two or more tangential vortices which extend from side to side of the basin. During the time the liquid is retained in the vortex an unusual opportunity for particle collisions is provided as the particles contained in the liquid are moved through a multiplicity of planes instead of the usual rotation in one plane.

Another characteristic of a vortex flow is that the velocity throughout tends to be substantially constant. Earlier flocculators tended to move quite slowly in order to avoid eddies and turbulence, but with a substantially constant velocity throughout the vortex, this limitation becomes less important. Thus the rotors may be driven with a higher speed than is generally thought permissible in flocculation, and I contemplate peripheral velocities from 2 to 3 feet per second. I have found that with the type of agitation and the flow pattern set up by these rotors some turbulence is permissible and often desirable. This may be due to the fact that the intricate flow pattern set up by these rotors provides such unusual opportunity for the contacting of old and new flocs and thus for building up of flocs which are tougher and less subject to breaking up than those formed by gentle paddle agitation. However, with the construction of the rotor, as described, higher velocities of the rotor do not cause the same increase in turbulence as would be the case with similar speeds of paddle agitators. It should be noted especially, that this type of rotor avoids setting up small violent eddies which are conducive to breaking up the flocs.

Each vortex has a tendency to maintain itself and liquid approaching it is positively drawn into it and incorporated into, and held in, the flow pattern of the vortex. Thus any short-circuiting of the liquid in a horizontal flow from inlet to outlet is prevented and in effect a plurality of individual treatment cells are set up. This result is obtained without use of costly baffles or the like, as was necessary in prior art structures, merely by applying a new positive type of agitation. In larger basins, where several rotors are used, they will be arranged symmetrically so that their vortices cover the entire area of the tank uniformly. The rotors should be close enough together that the vortices will be tangent. This permits some return of particles from a succeeding vortex to a preceding one. This return is gentle and non-turbulent, which

is different from most return of the prior art. The old art of flocculation did not provide for such gentle and unobstructed return flow from a later agitation unit back to a preceding one. 5 Where a return flow was provided in the prior art, it was either along the full length of the treating basin from outlet to inlet end and what was brought back in such case was in the form of sedimented and resuspended flocs whose value for coagulation is doubtful. Or the return flow was pumped back from unit to unit through narrow slotlike passages, whereby the flocs were in danger of being broken up. Contrary thereto, in the present invention the liquid with contained suspended particles is free to drift gently and unobstructedly from vortex to vortex, forwardly and, to some extent, backwardly. As the liquid is passed from unit to unit the solids, or flocs, are agglomerated into large, dense particles that have excellent settling and filtering qualities.

When one of the units is to be inspected or repaired, it will be taken out of service without disturbing the operation of the other units. The 25 whole assembly may be swung over to the wall of the basin, if the swingable type of support of Figure 3 is used, or, in the other embodiments, access is had over the beam 40 of Figure 1, or the bridge 51 of Figure 4. In any event the units are 30 easily accessible without draining the basin or disturbing operation when repairs become necessary. It will also be obvious that quite apart from the better accessibility it is generally a great advantage of the construction of this embodiment of my invention that it needs no submerged bearings.

Sometimes it is desirable that the rotors be mounted so that adjacent rotors will be rotated in opposite direction, such as rotor 30 at the left 40 side of the basin 10 of Figure 1 clockwise and rotor 30 at the right side of the basin counter-clockwise. I have found that, for example, such counter-current rotation of adjacent rotors is desirable when the plate 32 of the rotor is submerged, although with the plate mounted above the liquid level these rotors may be rotated in the same direction.

It will be seen that the coagulation or flocculation apparatus of my invention affords maximum opportunity for floc coagmentation and amassment with a minimum of structure. The construction of the coagulator is therefore relatively cheap. The floc produced is readily settleable or filterable, being tough and large.

55 It will be obvious that the embodiments shown and described are only illustrative examples and that my invention is not limited to the exact construction of these embodiments. Because of the small space required my flocculation apparatus 60 is very well suited for combined flocculation and sedimentation units and it will be understood that such a use is contemplated as coming within the scope of the invention. Thus, many changes could be made without departing from the spirit 65 and scope of the invention, and these changes will readily occur to those skilled in the art.

This application is a division of my copending application, Serial No. 771,968, filed September 3, 1947, now Patent No. 2,546,691, which is a continuation-in-part of my copending application, Serial No. 681,616, filed July 5, 1946, now abandoned.

I claim:

1. Coagulating apparatus comprising a basin, 75 an inlet into said basin, an outlet from said basin

remote from said inlet and establishing the normal liquid level in said basin, and a rotor interposed in the path of flow from said inlet to said outlet, said rotor comprising a power driven rotatable shaft extending vertically in said basin, a horizontal plate affixed to said shaft and having a diameter substantially less than the diameter of said basin, and at least twelve vertical blades rigidly mounted on the underside of said plate and extending inwardly from the periphery of said plate only partway to the center of said plate, the underwater length of said blades being greater than their width, the number of said blades being such that the maximum peripheral distance between individual blades is within the range of from about 15 to about 20 inches.

2. In a flocculation basin provided with an inlet and an outlet functionally remote from said inlet, an improved flocculating assembly comprising a rotatable vertical shaft extending axially within said basin, means for driving said shaft at a predetermined speed, and a liquid impelling member affixed to said shaft, said member having a diameter substantially smaller than the diameter of the basin and having a plurality of vertical blades rigidly affixed to and radially spaced from said shaft, the length of said blades being greater than their width, the pumping capacity of said liquid impelling member at said predetermined speed being several times the volume of the rated flow of liquid from said inlet to said outlet.

3. Apparatus for coagulating liquids comprising a basin adapted to hold liquid to be coagulated and having an inlet at one end thereof and an outlet at the other end, said basin being free of partitions obstructing flow therethrough, a plurality of coagulating units, each unit comprising a vertical rotatable shaft, a rotor affixed to said shaft, said rotor having a plurality of vertical blades surrounding said shaft in spaced relationship and being so constructed and arranged as to cause, on rotation of said shaft, a closed cycle vortex in liquid in said basin, a support for said shaft and means for driving said shaft, said coagulating units being symmetrically disposed in said basin in spaced relationship in such manner that the entire area of said basin is covered uniformly by the vortices set up by rotation of said rotors and that adjacent vortices are tangent.

4. In a coagulating apparatus comprising a coagulation basin having an inlet for liquid to be treated and an outlet for treated liquid, said basin providing a path for forward flow from said inlet to said outlet and being free of partitions deflecting said flow, unitary means effecting coagulation and preventing short-circuiting of liquid from said inlet to said outlet, said means consisting in a rotor assembly interposed in the flow from said inlet to said outlet, said rotor assembly having a diameter substantially smaller than the width of said basin, and comprising a vertical shaft axially extending in said basin, a horizontal plate rigidly secured to said shaft, vertical blades mounted on the underside of said plate and extending inwardly from its periphery only partway to said shaft, the length of said blades being less than the diameter of the rotor

and their width less than their length, and means for rotating said rotor at a predetermined speed, the pumping capacity of said rotor, at said predetermined speed, being sufficient to set up a three-dimensional vortex flow of a magnitude substantially in excess of the normal rated through-flow and to positively deflect the liquid to be treated from its forward flow from said inlet to said outlet and to incorporate it in said vortex flow.

5. An apparatus for developing flocs of a character favorable to rapid sedimentation comprising a coagulation chamber having an inlet for liquid to be treated and an outlet for treated liquid functionally remote from said inlet and establishing the normal liquid level in said basin, said basin being free of partitions obstructing flow from said inlet to said outlet, a rotor interposed in the path of flow from said inlet to said outlet, said rotor comprising a horizontal plate and a plurality of vertical blades mounted on the underside of said plate and extending inwardly from the periphery of said plate, the diameter of said plate being substantially smaller than the width of said basin, the length of said blades being substantially less than the diameter of said plate and their width less than their length, means for rotating said rotor with a peripheral velocity within the range of from two to three feet per second, said rotor, upon its rotation at such velocity, setting up a three-dimensional closed cycle flow of a magnitude at least twice the normal rated through-flow.

6. An apparatus for coagulation comprising a basin, a liquid inlet to said basin, a liquid outlet from said basin functionally spaced from said inlet, said basin being free of partitions interposed in the path of flow of liquid from said inlet to said outlet, a plurality of rotors in said basin, each rotor including a vertical shaft, a horizontal plate rigidly affixed to said shaft, and a plurality of vertical blades affixed to the underside of said plate and extending within the liquid in said basin, the length of said blades being less than the diameter of said plate and their width less than their length, means for causing rotation of said rotors, each rotor, upon rotation thereof, setting up a spiraling three-dimensional vortex of substantially larger diameter than the diameter of its plate, each rotor being positioned sufficiently spaced from the walls of said basin and from any other rotor in said basin in all directions of said vortex flow to prevent interference with said vortex flow by any wall and by the vortex flow of any other rotor.
